PATENT NO. : Des. 551,100 S
APPLICATION NO. : 29/234043
DATED : September 18, 2007
INVENTOR(S) : Tetsuo Okaya

It is certified that error appears in the above-identified patent and that said Letters Patent is hereby corrected as shown below:

The title page, showing an illustrative figure, should be deleted and substitute therefor the attached title page.

Delete drawing sheets 1 – 4, and substitute therefor the drawing sheets consisting of FIGS. 1 – 7 as shown on the attached pages.

Signed and Sealed this

Eleventh Day of December, 2007

JON W. DUDAS
Director of the United States Patent and Trademark Office
